SAFETY REEL FOR A BLASTING CABLE

Frank W. Brown, Elkridge, W. Va.

Application March 27, 1935, Serial No. 13,362

1 Claim. (Cl. 242—77)

The invention relates to a blasting cable carrier or reel and more especially to a safety reel for a blasting cable.

The primary object of the invention is the provision of a reel of this character, wherein a short circuiting switch is carried thereby and the same is closed when the cable is wound upon the reel so that it is impossible for one to come in contact with an electric current when attaching the cable to the blasting cap and such switch can not be opened until the cable has been worked off of the reel thereby preventing injury to the user of the reel.

Another object of the invention is the provision of a reel of this character, wherein the construction thereof is novel in form and will support a blasting cable as employed by miners for blasting purposes, the reel being made safe against theft and also assures safety against accidental injury when connecting the cable with a blasting cap of the electric type.

A further object of the invention is the provision of a reel of this character which is simple in construction, thoroughly reliable and efficient in its operation, strong, durable and inexpensive to manufacture.

With these and other objects in view, the invention consists in the features of construction, combination and arrangement of parts as will be hereinafter more fully described, illustrated in the accompanying drawing, which discloses the preferred embodiment of the invention and pointed out in the claim hereunto appended.

In the accompanying drawing:

Figure 1 is an elevation of a reel constructed in accordance with the invention.

Figure 2 is a vertical transverse sectional view thereof.

Similar reference characters indicate corresponding parts throughout the several views in the drawing.

Referring to the drawing in detail, A designates generally a portion of a post or upright constituting a support for the reel embodying the present invention and hereinafter fully described.

The reel comprises a center hub 5 in the form of a metal sleeve with which are connected inner and outer spaced radially disposed wire spokes 6 which are provided with coils 7 to embrace the perimeter rings 8 of the reel. The opposed coils 7 each have extending from one of their ends inwardly rounded portions 9 that provide the valley members for permitting the seating of a blasting cable 10 in the reel on the winding of the said cable thereon. It will be noted that each of the

opposed pair of spokes has a valley member integrally formed therewith and that the said spokes are of a substantially U-shaped formation. The hub 5 is rotatably fitted upon a journal screw 11 which is secured into the support A for the rotation of such reel when winding the cable 10 thereon or on the unwinding of the cable therefrom.

Made fast to the post A by a staple 12 is a chain 13, the same being adapted for engagement about one of the spokes 6 at the inner side of the reel 10 and be fastened by a lock 14 so as to avoid theft of the reel, the chain 13 being freed from the reel when the latter is to be turned.

Disposed crosswise of the reel and carried by an insulating base 15 upon hangers 16 suitably fastened to pairs of adjacent spokes is a short circuiting switch 17 having the swinging blade 18 and with the switch are connected the current wires 19 of the cable 10. The blade 18 of the switch 17 is disposed so that when the blade 18 is closed the cable when wound upon the reel will prevent the opening of the switch by opening the blade 18 thereof until the cable 10 has been worked off of the reel, the cable being engaged in a clip 20 carried by the hub 5 so as to avoid any strain upon the connections of the wires 19 of this cable with the switch 17 when unwinding the cable from the reel.

When the switch blade 18 is closed the current is short circuited at the point of the switch 17 so that connections of the cable with the electric blasting cap can be had without injury to a person by contacting with the current wires charged with current as the current will not flow through the cap until the switch 17 is opened and this is accomplished on completely letting off the cable from the reel.

At certain of the spokes 6 at the outer side of the reel are hooks 21 for the engagement of the cable therein at its outer free end when wound upon the reel for the holding of this end of the cable. These hooks are also in the nature of wire members and have their ends coiled around the ring members 8 at the opposite sides of the spokes and contact with the coiled portions of said spokes to prevent any tendency of the spokes moving on the ring members or the said ring members moving circumferentially through the coils of the spokes.

On the ring 8 of the reel at the outer side thereof is a wire gate member 22 which when thrown from the position shown by full lines in Figure 2 to the position shown by dotted lines in said Figure 2 of the drawing will hold the cable from riding from the reel and out of the

valley piece 9 next to said member 22. The gate 22 has one of its ends loosely coiled around one of the ring members 8 and the coils of one of the spokes 6 are spread to receive this part of the gate as shown in Figure 1 of the drawing.

It is, of course, understood that before winding the cable 10 upon the reel the switch 17 is closed and the latter retained in this condition until the cable has been let off from the reel.

10. What is claimed is:

A reel for the purpose set forth, including a hub and spokes radiating from said hub, each of said spokes comprising, a wire member which is substantially U-shaped in plan and whose parallel arms have their ends fixed to the hub, the

said arms at their outer ends being coiled upon themselves, rings received through said coils, the connecting portions of said arms between the rings being bowed in the direction of the hub to provide cable receiving valleys, hooks each comprising a wire member engaged with one of the rings and bent to provide a beak and arms coiled around said ring and in contact with the opposed sides of the coiled portions of the arms of the spokes, and a coiled wire gate comprising an angle member approximately centrally mounted on one of the rings and designed to have one of its arms normally swung over the second or opposite ring.
